Margaret Michelson, New York, N. Y.

Application July 3, 1937, Serial No. 70,240

Term of patent 3½ years

To all whom it may concern:

Be it known that I, Margaret Michelson, a citizen of the United States of America, residing in Manhattan, county of New York, and State of New York, have invented a new, original, and ornamental Design for a Dress, of which the following is a specification, reference being had to the accompanying drawing, forming part hereof, wherein,

Figure 1 is a front view of a dress showing my new design.

Figure 2 is a rear view of the dress shown in Figure 1.

The characteristic feature of my design resides in the combination on the net dress as shown of the specific embroidery in association with bows at the neck and belt lines, and leather trimming on the collar and sleeve edges.

I claim:

The ornamental design for a dress, substantially as shown, and described.

MARGARET MICHELSON.
